UNITED STATES PATENT OFFICE.

FRANK N. WATT, OF RICHMOND, INDIANA.

BURIAL CASKET.

Application filed April 12, 1926. Serial No. 101,358.

The object of my present invention, broadly speaking, is to provide a burial casket which incorporates therein certain new, novel, and useful features, the same being simple in construction, neat and attractive in appearance, practically automatic in operation, and which can be manufactured and sold at a comparatively low price.

More specifically stated, my object is to provide a burial casket provided with a hinged lid or cover therefor, and having a drop front also hinged to the body of the casket, and having means whereby the front will automatically open and close simultaneously with the opening and the closing of the lid, the operations of the front being controlled by the operations of the lid, and having means whereby the lid will be secured in open position, to be released only by means which are manually instituted.

Other minor objects and particular advantages of the invention will suggest themselves in the course of the following description and that which is new will be correlated in the appended claims.

The preferred means for carrying out the principles of my invention in a practical, efficient, and economical manner, is shown in the accompanying two sheets of drawings, in which Figure 1 is a front elevation of one end portion of a casket, showing the lid and the drop front in closed position. Figure 2 is a perspective view of one end portion of a casket, showing the lid and the drop front in open position. Figure 3 is a cross section of a casket, showing the positions of the mechanism, attached to the end, when the casket is in closed position. Figure 4 is the same as Fig. 3, except that the parts are shown as they would appear when the casket is in open position.

Figure 5 is a detail view, showing a portion of the telescoping arm. And Figure 6 is a longitudinal section of a portion of the casket, showing that part of the mechanism carried by the front, taken at right angles to that shown in Figs. 3 and 4.

Similar indices denote like parts throughout the several views. In order that the construction, the operation, and the advantages of my invention may be more fully understood and appreciated, I will now take up a detailed description thereof, in which I will set forth the same as comprehensively as I may.

In the drawings letter A denotes the bot-

tom of a casket. B denotes the back. C denotes the stationary part of the front. D denotes one end, the other end not being shown. And E denotes the top. The top E 60 is hinged to the back B by a plurality of hinges, as the hinge F. Letter G denotes the drop front, which is simply a portion of the front C cut away, as shown, and it is hinged to the part C by the hinges H. 65

All of said parts are of ordinary construction, and I make no claim thereto per se, but only in combination with the mechanism.

The invention proper resides in the mechanism which I will now describe in concrete detail.

Numeral 1 denotes a hollow or tubular arm, its upper end being flattened and connected to the lid E, inside thereof, by the pivot 2. Rigid with and connected around the lower end of the arm 1 is the stop member 3. Slidable inside the member 1 is the auxiliary arm 4, and it extends out through the lower end of the member 1, and its projecting end portion is provided with a disc-like bearing 5, which has an aperture 6 therethrough to receive the pivot 7, by which the arm 4 is pivoted to the rear end of the link 8.

Numeral 9 denotes a guard, which is secured diagonally to the inner face of the end D, by means of screws or nails 10. The arm 1 may slide endwise in the guard 9, and said guard also permits the arm 1 to have a limited movement sidewise, as indicated.

Numeral 11 denotes a catch, which is connected to the end D by the pivot 12, with its upper end or point adapted to engage the stop 3, to prevent the arm 1 from moving downward, that is to say, locking the lid in open position. Numeral 13 denotes an arm, which is rigidly secured at its lower end to the lower end of the catch 11, as by the rivets 14. The upper portion of the arm 13 operates in the guard 15, which permits said arm to have only a limited forward and rearward movement. The guard 15 is secured to the inner face of the end D, as by the screws 16.

By reason of the position of the pivot 12 it will be seen that gravity will normally cause the upper end of the arm 13 to be to the right, as shown in Fig. 3, in which position it will engage the stop 3. But it may be moved manually to the left, as in Fig. 4, which will release the stop 3, and therefore

permit the arm 1 to slide to the position shown in Fig. 3.

Numeral 17 denotes a shaft, which is rotatably mounted in the bearings 18 and 19 which are secured to the side C, near to and to one side of the front G, as shown in Fig. 6. Said shaft approaches at its outer end near to the end D, and on its outer end a crank 20 is rigidly connected therewith, and projecting inward at right angles thereto. The inner end of the crank 20 is connected to the forward end of the link 8 by the pivot 21.

Also rigidly connected with the shaft 17, and located at the inner end thereof, is the curved and flattened arm 22.

Formed in the lower portion of the inner face of the front G is a notch 23, in which the flat portion of the arm 22 may freely operate, but without direct attachment to the front G.

Secured to the inner face of the front G and covering the notch 23, and also covering the flattened portion of the arm 22, is the cap 24, with which the arm 22 may engage when the said arm is moved upward and inward, in order to turn the front G therewith.

All of the mechanism above described will be covered by the trimmings, usually placed upon the casket, except the arm 1 and the upper end of the arm 13, as shown in Fig. 2.

When the casket is closed it will appear as in Fig. 1, except that hinges H would be covered with the trimmings, in which position the mechanism will assume the position shown in Fig. 3. Now if the lid E be lifted and turned on its hinges F then in this operation the mechanism will gradually assume the position shown in Fig. 4, except that the point of the catch 11 will automatically engage the stop 3, thereby locking the lid in open position, to be released only by turning the arm 13 to the left, as in Fig. 4.

As the lid E is turned upward and backward it is evident that the arm 1 will move through the guard 9 until the stop 3 engages the said guard 9, which will be simultaneously with the catch 11 engaging the stop 3, thereby preventing the lid from being turned further back than is desired, that is to vertical position as shown. As the arm 1, in connection with the auxiliary arm 4, moves back it will pull the link 8, and it in turn will cause the crank 20 to move upward, thereby turning the shaft 17. This last mentioned movement will cause the arm 22 to turn outward and downward, carrying with it the movable front G, thereby causing the front G to assume open position, as in Figs. 2 and 4, simultaneously with the lid E assuming open position.

It should be noticed that the stop 3, when the point of the catch 11 is in engagement therewith and when the stop 3 is in engage-

ment with the guard 9, prevents the lid from being turned either forward or backward, thereby locking it in its open position.

Also it will be observed that it is necessary that the arms 1 and 4 be telescopically connected, not only to permit the proper flexibility to the mechanism, but permitting the combined arm, 1-4, to be longer or shorter at times, in order that the movements of the front G may be automatically timed to the movements of the lid E.

In action the operation is such that the lid E will move upward for a short distance from closed position before the front G starts to move, this being caused by the member 1 moving without moving the member 4. Also when being closed the front G will close a short time before the lid E is closed, these results being obtained by reason of the telescoping mounting of members 1 and 4.

When one desires to close the lid all that is required is for the attendant to press rearward on the exposed upper end of the arm 13, which will release the catch 11 from the stop 3, and then the lid E may be easily lowered to closed position, with the front G closing automatically during the interval of closing the lid E, but the front G will accomplish its movements in less time than does the lid E.

Having now fully shown and described the best manner for the construction and carrying out of my invention, I desire that it be understood that various changes may be made in the details thereof without departing from the spirit of the invention and without sacrificing any of the advantages thereof which are new and useful.

What I claim and desire to secure by Letters Patent of the United States is—

1. In combination with a burial casket having a hinged lid, a front consisting of a stationary portion and a hinged portion; a telescoping arm connected at its upper end to the lid, a link pivoted to the lower end of said arm, a shaft rotatably mounted to the inner side of the stationary part of the front, a crank extending at right angles from said shaft and pivoted to said link, a curved arm connected to said shaft and contacting with the hinged front but without direct attachment thereto, and a cap secured to the inner face of the hinged front and surrounding a portion of said curved arm but without direct attachment thereto.

2. In combination with a burial casket having a hinged lid and a front comprising a stationary portion and a hinged portion; a telescoping arm connected at one end to said lid, a link pivoted to the other end of said arm, a shaft rotatably mounted to the inner face of the stationary part of the front, a crank extending inward from said shaft and pivoted to said link, a curved arm extending at right angles from said shaft and contact-

ing with the inner side of said hinged member of the front but without direct attachment thereto, a cap secured to the inner face of the hinged member of the front and surrounding a portion of said curved arm but without direct attachment thereto, a guard secured to the inner face of the end of the casket with said telescoping arm adapted to slide therein, a stop carried by the telescoping arm and adapted to engage said guard

to prevent the lid from moving backward beyond vertical position, a catch adapted to automatically engage said stop when the lip is in vertical position to prevent the lid from being closed, and means for manually releasing said catch to permit the lid to close. 15

In testimony whereof I have hereunto subscribed my name to this specification.

FRANK N. WATT.
